(57) **CLAIM**

The ornamental design for a lavatory console, as shown and described.

DESCRIPTION

FIG. 1 is front perspective view of the lavatory console of the subject invention;

FIG. 2 is a front view thereof;

FIG. 3 is a rear view thereof;

FIG. 4 is a right side view thereof, the left side being a mirror image of the right side shown; and,

FIG. 5 is a top view thereof.

The broken line representations are for illustrative purposes only and form no part of the claimed design.
